Primary Examiner — Lucy Lieberman(74) *Attorney, Agent, or Firm* — Fitch, Even, Tabin & Flannery(57) **CLAIM**

We claim the ornamental design for a water timer, as shown and described.

DESCRIPTION

FIG. 1 is a top, front and right side perspective view of a water timer showing our new design;

FIG. 2 is a front elevational view of the water timer of FIG. 1; FIG. 3 is a left side elevational view of the water timer of FIG. 1;

FIG. 4 is a right side elevational view of the water timer of FIG. 1;

FIG. 5 is a rear elevational view of the water timer of FIG. 1; FIG. 6 is a top view of the water timer of FIG. 1; and, FIG. 7 is a bottom view of the water timer of FIG. 1.

The broken lines in the foregoing drawings are for the purpose of illustration and form no part of the claimed design.
